VENTILATOR

John Marshall, Pollokshaws, Glasgow, Scotland

Application December 4, 1936, Serial No. 114,123
In Great Britain March 17, 1936

4 Claims. (Cl. 98—41)

This invention relates to ventilators, especially for use in roofs or ceilings.

An object of the invention is to provide a ventilator comprising a flared member, an intermediate apertured baffle member, an outer disc or baffle plate member and means for adjusting said members into predetermined relative positions the flared member, the apertured baffle member and the outer baffle member being adjustable into three relative positions, a fully open position in which said members are spaced apart to form two air passages, an intermediate position in which two of the members assume nested relationship leaving only one passage, and a fully closed position in which all three members assume nested positions.

In order that the invention may be particularly described and ascertained it will now be described by way of example with reference to the accompanying drawing in which:

Fig. 1 is a sectional elevation of a ventilator in accordance with the invention.

Fig. 2 is a corresponding plan view.

As shown, the ventilator is fixed in an opening 1 in a roof or ceiling communicating with an air supply duct 2 and comprises an outer flared member 3, an intermediate flared annulus member 4, and a lower disc or plate member 5. The disc 5 also prevents direct downward blow of air these members 3, 4 and 5 respectively having annular parts 3a, 4a and 5a of convex shape regarded from below and adapted to engage in nested relationship as hereinafter described. In the position shown in Fig. 1 the flared member 3, the annulus 4 and the disc 5 constitute upper and lower air discharge passages respectively denoted by the numerals 6 and 7.

The member 3 is supported in the opening 1 and has attached thereto a three-armed spider 8 carrying a central boss 9 in which slidably engages a central spindle 18 supporting at its lower end the disc 5 and an adjusting handle 10. The spindle 18 is provided with three vertically spaced annular grooves 11 any one of which is engageable by three rounded projections 12 located in the boss 9 which has radial enlargements 9a to accommodate these projections which are inwardly urged by resilient means such as a rubber member 13, spring or the like, to retain the spindle 18 in any of three vertically adjusted positions.

The intermediate annulus 4 is supported by three angularly spaced brackets 14 attached thereto and attached to, or formed integrally with, a washer 15 supported on the boss 9 and retained in position by a cap 16 itself retained in

position by a split pin 17 passing through the spindle.

In the position shown in Fig. 1, the ventilator is fully open, air being discharged through the upper and lower passages. The flared member 3, the annulus 4 and disc 5 in that order are of decreasing size, but the annulus 4 is of greater size than the opening 1 while the disc 5 is of greater size than the opening 4b in the annulus 4, so that the annulus and disc act to baffle and diffuse the air discharged through the openings 1 and 4b.

By raising the spindle 18 until the middle notch 11 is engaged by the projections 12, the lower passage 7 is closed by the convex part 5a of the disc 5 coming into nested relationship with the annulus 4 and closing the opening 4b thereof. Similarly the upper passage 6 can be closed by further raising the spindle 18 until the lowest groove 11 is engaged by the projection 12. Thereupon the convex part 4a of the annulus 4, already engaged by the disc 5, comes into nested relationship with the convex part 3a of the flared member 3 and closes the opening 1.

The above description having been given merely by way of example, it follows that modifications may be made without departing from the scope of the invention. For example, guide means may be provided to prevent rotation of the annulus 4 or disc 5. Such means may comprise upward projections on the disc and the annulus adapted slidably to engage a fixed part such as the spider arms or other part connected to the flared member 3.

To prevent noise in closing and/or to provide more effective closure, sound-adsorbing and/or packing material may be provided on the arcuate portions 3a, 4a and 5a of the members 3, 4 and 5.

The ventilator may include or consist mainly of parts made of sheet metal, for example, brass, or may include or consist mainly of parts made of mouldable plastics such as synthetic resinoid substances, vulcanite or the like.

I claim:

1. A ventilator comprising a fixed flared member, an intermediate apertured baffle member, an outer baffle member, means for movably connecting said apertured baffle member and said outer baffle member to the flared member so as to be relatively movable to each other and to the flared member, and means for holding said members in predetermined relative positions including closed, fully open and at least one intermediate position, the outer member being adapted to engage the apertured member and to move together with 55

same during the final part of the closing movement.

2. A ventilator comprising a fixed flared member, an intermediate apertured baffle member, an outer baffle member, fixed support means for movably supporting said apertured member and said outer baffle member, a spindle to which said outer baffle member is attached and which is slidable in said support means, spaced retaining means on the spindle adapted to engage with said support means and hold said outer baffle member in spaced relationship to the intermediate baffle and the fixed flared member, and hold said outer baffle member in closed relationship with the intermediate baffle member but spaced from the fixed flared member and hold said outer baffle member and intermediate member in closed relationship with each other and the fixed flared member, the outer baffle member being adapted to engage the apertured member and to move together with same during the final part of the closing movement.

3. A ventilator comprising a fixed flared member, an intermediate apertured baffle member, an outer baffle member, means for supporting said apertured and outer baffle members movably with reference to the flared member and to each other and means for maintaining said members in three relative positions, a fully open position in which

said members are spaced apart to form two air passages, an intermediate position in which two of the members assume nested relationship and close one of said passages, and a fully closed position in which all three members assume nested relationship. 5

4. A ventilator comprising a fixed flared member, a central support thereon, an intermediate annular baffle member slidably supported on said support, an outer baffle plate member, a spindle 10 thereon slidably engaging said support, three longitudinally spaced recesses on the spindle and spring urged projection means in the support for engaging said recesses, each member having a part of convex shape regarded from the air discharge side and said members being slidably adjustable into three relative positions in which they are maintained by said recesses and projection means, said positions consisting of a fully open position in which said members are spaced 20 apart to form two air passages, an intermediate position in which the convex parts of the outer baffle plate and the intermediate baffle assume nested relationship and close the outer air passage and a fully closed position in which said 25 last-mentioned convex parts assume nested relationship with the convex part of the flared member and close the remaining air passage.

JOHN MARSHALL.
